UNITED STATES PATENT OFFICE

ATHERTON H. MEARS, OF PHILADELPHIA, PENNSYLVANIA, ASSIGNOR TO LEEDS & NORTHRUP COMPANY, OF PHILADELPHIA, PENNSYLVANIA, A CORPORATION OF PENNSYLVANIA

APPARATUS FOR SPEED GOVERNING

Application filed June 30, 1931. Serial No. 548,051.

My invention relates to governor mechanism for maintaining constant the speed of a motor used for timing purposes, or any purpose requiring high degree of constancy.

5 In accordance with my invention, the effect of ambient temperature upon a governor controlling the speed of a motor, is compensated by a thermostatic element; more particularly a bimetallic strip maintains the stiffness 19 of the spring system of the governor constant irrespective of substantial variations in ambient temperature.

15 My invention further resides in the features of construction, combination and arrangement hereinafter described and claimed.

For an understanding of my invention and some of the various forms it may take, reference is to be had to the accompanying drawings in which:

20 Fig. 1 is an elevational view of the rotatable governor structure, and Fig. 1a is a modification thereof.

Fig. 2 is an inverted plan view of stationary structure and elements movably supported thereon.

25 Fig. 3 is an elevational view of the structure shown in Fig. 2.

Fig. 4 is a side elevational view showing in part the structure of Figs. 1 and 2 in operative relation.

30 Fig. 5 is a view showing the relation between certain parts of the governing mechanism.

Fig. 6 is an elevational view, partly in section, illustrating another type of governor driven by and controlling the speed of a motor.

35 Fig. 7 is an elevational view on enlarged scale with parts in section of the governor shown in Fig. 6.

Fig. 8 is a top plan view of part of the stationary governor element.

40 Fig. 8a is a top plan view of part of the stationary element of another modification.

Fig. 9 is a bottom plan view of the rotatable governor element of Fig. 7.

45 Fig. 10 is a detail view taken on line 10—10, Fig. 7.

50 Referring to Figs. 1 to 4 inclusive, frame 27 of the governor mechanism is attached to

the shaft 1 of a motor M whose speed is to be controlled, by a set screw 10 or in any other desired manner. The centrifugal member or flyball 28 which may be weighted in any well known manner, is attached to shaft 29 through arm 28a rotatable in the upper end of bifurcated extension 30 of frame 27 and is freely movable between the head of the adjustable screw 31, which passes freely through the weighted end thereof, and a stop frame 32 which threadedly receives the stop screw 31. Stop frame 32 is secured to frame 27 as by screw 13. A spring 33 passing through opening 11 in hub portion 34 of the frame 27 and through the stop member 32 60 engages at one end the movable centrifugal element 28, as by pin 12, and at its other end the pin 35 extending downwardly of frame 27.

55 A light frame work 36 movable with the flyball structure 28 passes freely through a slot 14 in a hub portion 37 of frame 27. On the upper end of hub 37 is secured an eccentric cam 38 which operates in a manner hereinafter described. Frame 36 terminates in a threaded rod portion 39 extending substantially parallel to the axis of rotation of frame 27 and has adjustably clamped thereto a disc 40 concentric with respect to the axis of rotation of frame 27.

65 Referring more specifically to Figs. 2 and 3, a fixed supporting member 44 is adapted to be mounted independently of the motor M and its rotating governor structure 27. Support 44 has pivotally mounted thereon at 43 a frame or switch-supporting member 42. As illustrated in Fig. 3 member 42 is pivoted at one end, and at its other end has extending arms 41, spaced as illustrated in Fig. 2, so as to engage the periphery of cam 38 at diametrically opposite points. Member 42 has pivotally mounted thereon at 16 a switch member 47 which is bodily carried thereby. It

70 will be apparent therefore that movement of the member 42 about its pivot 43 will also effect movement of switch member 47 in substantially the same manner. An insulating support 49, connected as by bolt 49a to the fixed support 44, carries a fixed contact 48 which is adapted to be engaged by one end

of switch member 47. Assuming that switch member 47 is in engagement with contact 48 as indicated in Fig. 2, oscillation of member 42 about its pivot 43 will simply cause rotation of switch member 47 also about substantially the same point and switch member 47 will remain in engagement with contact 48. In the same manner, switch member 47, if out of engagement with contact 48, would remain in such position during oscillation of the switch-supporting member 42.

If now, however, the end of switch member 47 on the other side of its pivot 16 were to be kept from rotating with member 42, as 15 by engagement with some stationary member, it will be apparent that the contact engaging end of switch member 47 would oscillate through an arc dependent on the movement of member 42, and would therefore intermittently engage contact 48.

Referring to Fig. 4, apparatus for oscillating member 42 is illustrated.

The periphery of the eccentric 38 is engaged by the lower edges of the downwardly 25 extending arms 41 of the frame or support 42 pivoted at 43. The fixed support 44 carries a cross arm 45 of suitable insulating material, the opposite ends of which are each provided with a binding post 46. Upon the frame 42, 30 which is adapted to be oscillated by cam 38 during energization of motor M, the movable switch member 47, preferably a contact member, is suitably electrically connected to a terminal 46, as by conductor 15, and adapted 35 to engage the contact 48 carried by block 49. Contact 48 is electrically connected to a terminal 46 as by a conductor 17. Contact member 47 is provided at its opposite end with two actuating arms 50 and 51 disposed in 40 different planes, as shown most clearly in Fig. 5, and adapted to alternately engage the disc 40 during oscillation of frame 42 by cam 38 when disc 40 is in predetermined limiting positions.

45 The coaction between the switch actuating arms and member 40 may be best explained by reference to Figs. 2, 3 and 5. Switch member 47 is cut away as at 47a so that the members projecting above disc 40 may not 50 interfere with movement of the disc with respect to the switch actuating arms 50 and 51. Referring more particularly to Fig. 5, disc 40 is shown in its neutral position and will not be engaged by either arm 50 or 51. 55 In case disc 40 should take a lower position, due to increase in speed of motor M, it would be engaged by the laterally extending arm 51. In the same manner, elevation of disc 40 would put it in the path of arm 50 which 60 would engage the disc, and thereupon actuate the switch member. Member 47 is cut away as indicated in Fig. 3 so that disc 40 will not engage any portion of arm 51 until it has 65 reached a predetermined low position. Switch member 47 may comprise simply a

metal stamping having arms 50 and 51 bent at right angles thereto.

The governor thus far described is similar to that of my Patent 1,797,510 granted March 24, 1931 to which reference is here made for more detailed description of its operation.

It is characteristic of spring governors in general, that the speed which they maintain constant varies with changes in ambient temperature; i. e., the speed will be held constant at one value for a certain temperature and at another value for a different temperature. This is undesirable, particularly when the motor is utilized for timing purposes, for example, for driving a recorder chart or sheet.

Upon decrease of ambient temperature, for example, the bracing action or force exerted by the spring 33 tends to increase, as the length of the spring decreases, assuming that the material comprising it has a positive temperature coefficient, and the elasticity of the spring increases. As a result, the governor holds the speed constant at a higher value for the lower temperature. Conversely upon increase of ambient temperature, the governor holds the speed constant at a lower value. The integrated speed of the motor, or total number of revolutions over a period of time therefore depends upon the ambient temperature though the motor speed is held constant for each temperature value. Changes in temperature may also affect the dimensions of other governor parts.

In accordance with my present invention, the motor speed is made independent of ambient temperature or changes in ambient temperature, at least throughout a substantial range of variation. In a governor of the construction described, the compensation is automatically applied whenever necessary and while the motor is running.

Referring to Fig. 1, the free end of an arm 53, pivoted to a member 54 extending below support 44, bears upon the top of the threaded extension 39 of the fly-ball frame 36. Between arm 53 and a thermostatic element 55 is interposed an auxiliary spring 56 whose stiffness is less than that of the bimetallic strip 55. Assuming that spring 33 has a positive temperature coefficient, i. e. it 105 lengthens with increase in temperature and therefore becomes weaker with higher temperatures, bimetallic strip 55 is disposed with the metal having the greater temperature coefficient on the under side so that strip as a 110 whole curves downwardly upon decrease of temperature. The resulting increased compression of auxiliary spring 56 compensates for the increased tension of spring 33 at the lower temperature maintaining constant the 115 effective force restraining movement of the flyball by centrifugal action.

Conversely with increases of ambient temperature, the thermostat 55 relieves to corresponding extent the compression of spring 120

56 so that the differential of the forces exerted by spring 56 and 33 upon the flyball remains constant. Otherwise stated, the stiffness of the governor spring system remains constant for changes in ambient temperature so that the motor speed is independent of temperature variations.

More generally, the bimetallic strip may compensate not only for the effect of temperature upon the spring but upon other governor parts as well or in other words for the net effect of temperature upon the governor.

The same result may be obtained with the construction shown in Fig. 1a. In this modification, the post 35 of Fig. 1 for holding one end of governor spring 33 is replaced by the bimetallic strip 55a which bends upon change of temperature to compensate for the effect of the temperature change upon the governor. The arm 53, spring 56 and associated parts are of course, omitted. The remainder of the governor construction is the same as that of Figs. 1 to 5.

My invention is not limited for use with my harmonic governor but is applicable to any governor whose spring tension may be varied while the motor is running. In Figs. 6 to 10, there is illustrated a governor similar to that disclosed and claimed in copending Wunsch application Serial No. 158,372, filed December 31, 1926, suitably modified to include the feature of compensating for the effect of temperature.

Referring to Fig. 6, M is a motor having a rotatable armature fastened on a shaft 61 mounted in bearings in the usual manner. A worm gear 62 fastened to the shaft 61 is in engagement with a worm wheel 63 to drive a shaft 64 connected by means of the gear 65 to any suitable device or mechanism whose speed is to be controlled with great precision. It is to be understood, however, that such mechanism may be directly driven from the shaft 61. The rotatable element 66 of the governor is held in any suitable manner, such as by a set screw, to an end of the shaft 61 and rotates therewith. The stationary or contact-carrying member of the governor 67 is rigidly clamped to the housing 68 which may also serve as a mounting for the motor M, as shown.

The hub portion of the rotating or centrifugal element 66 is provided with a bore 69 to receive an extension of the shaft 61, which is locked in position by means of a set screw 70. Fastened to, or integral with the hub portion, is a yoke or U-shaped member, provided with pins 71 and 76, each of which extends transversely through the free end of a leg of the yoke. The pin 71 serves as a pivot for a slotted, L-shaped member 72, which, at an extreme end, is adapted to receive the end of a tension spring 73. The shoulder-portion of a screw 72a, threaded into the yoke member, is utilized as an ad-

justable stop for moving the slotted member 72 to obtain a desired tension of the spring 73. The head of the screw 72a, extends through the slot in member 72 to facilitate an adjustment of the screw by means of a screw-driver, or other suitable tool. When the desired adjustment has been made, the screw may be locked in position by the clamping screw 72b, or in any other suitable manner. The spring 73, passes through a hole in the hub portion of the movable member 66, and is fastened at its other end to the threaded extension of a flyball 74, secured to one extremity of a pivotal member 75. The other extremity of the member 75, which is pivoted on pin 76, is provided with downwardly extending lugs 75a, having each a hooked portion for a purpose hereinafter described. Passing through the same end of this member and held fast thereto by means of the clamping nuts 78, is a bearing member 77, preferably of fibre, which cooperates with a part of the stationary or contact-carrying structure in the axis of rotation of the rotating element. When the speed of the motor is below the desired or critical speed, the member 75 is biased by means of the spring 73 to the position shown in Fig. 7. The strength of the spring bias, as previously described, is adjustable by means of the screw 72a and the lever 72. When the motor speed is higher than the desired speed, the centrifugal force acting on the flyball 74 overcomes the tension of the spring 73, modified as hereinafter described, and causes member 75 to rotate about pin 76 in a clockwise direction.

The stationary or contact-carrying member of the governor consists of a plate 79, having a pair of upturned lugs 80, through which extends the pivot pin 81. A movable member 82, is provided with bearings in a pair of projecting ears, which cooperate with the pin 81. On one side of the pivot, the member 82 has a slot 83, to provide a ready means for adjustably positioning a movable contact member 84, which is held in the desired position by a nut or other suitable means. On the other side of the pivot point, the member 82 has an extension 85 bent at an angle thereto, which receives an end of a relatively-fine, tension spring 86. The plate 79 is formed with an upwardly extending portion 103, which locates the pin 88a, on which is pivoted the bifurcated L-shaped member 88, to which is attached the bimetallic strip 55' engaging the other end of the spring 86. A screw 88b is threaded into a tapped hole in the upstanding portion 103 and has a shoulder portion which serves as an adjustable limiting-stop for the member 88. An extension of this screw passes through a slot in the member 88, to provide a ready means for adjusting the tension of the spring 86. The bimetallic strip 55' is materially stiffer than spring 86.

The movable member 82 is provided with a button 87, preferably made of some wear-resisting material or hardened to prevent wear, which is intended to be in contact with the 5 fiber bearing member 77 of the rotating element, during normal operation of the governor. This member, which is fastened in any suitable manner to the member 82, such as by riveting, is so shaped that the hooked 10 portions of the downwardly extending ears 75a of the member 75 may, under circumstances to be later described, cause the rotation of the movable member 82 about its axis 81.

15 It should be noted at this point that the spring 86 tends to cause the rotation of the movable member 82 in a clockwise direction, and, since this member is, by means of the button 87, in engagement with the member 20 75, it also tends to cause the clockwise rotation of the latter about its axis 76, which tendency is contrary to that due to spring 73. When the device is at rest, the screw 72a may be adjusted to regulate the tension of spring 25 73 through a considerable range, which serves as a rough adjustment for approximating a desired speed or angular velocity. Since the spring 86 is opposite in effect on the member 75 to that of spring 73 and the 30 adjusting means therefor is on the stationary plate 79, it is apparent that a desired operating velocity of the governor can be precisely effected by this latter adjustment, even while the motor is running.

35 The relative positions of the movable and stationary members of the governor are such that when the motor is running below the critical speed, the bearing members 77 and 87 are just touching in line with the axis of rotation of the centrifugal member, and the contacts are closed. When the speed of the motor rises above that point, the member 75 rotates in a clockwise direction about its axis 76 as described and the contact member 82 40 follows it under the influence of spring 86. If, however, the contacts tend to stick or weld, the hooked portions 75a, of the member 75, after a slight movement, engage the under side of the button 87 and cause positive 45 movement of member 82 to separate them.

A threaded member 89 is riveted or otherwise fastened to the plate 79 and serves both as a means for conducting the current to the movable contact and for holding the plate 50 55 in a fixed position. The contact 91 is carried by a slotted bracket extending from a ring 92, which is in contact with a threaded sleeve 93, surrounding the extension 89, but insulated therefrom by the sleeve of insulation 99 and separated from the plate 79 by an insulating washer 95. An insulating collar 100 prevents the sleeve from making contact with the housing 68. A lug 94, in contact with the sleeve 93, provides a means for 60 65 conducting current to the stationary contact 91.

The nut 98, threaded on the flanged sleeve 93, clamps ring 92, lug 94 and insulating washers 96 and 97 to the housing, as shown in Fig. 7. The plate 79 is held rigid with this assembly by means of the clamping nut 101 and the insulating washer 102.

The effect of ambient temperature upon the spring system of the governor is compensated by the bimetallic element 55' substantially in the manner previously described in 75 connection with the preceding modification. The bimetallic element 55' bends to the left as viewed in Fig. 8 upon decrease of ambient temperature increasing the tension of spring 86 to counteract the increased tension of 80 spring 73 and conversely upon increase of temperature the tension of spring 86 is relieved by bending of the bimetallic element to the right. In some cases, if the effect of temperature upon spring 86 is greater than 85 its effect upon spring 73, it may be necessary to reverse the bimetallic strip to obtain the compensating action.

A further modification of my compensating system is shown in Fig. 8a, which in some respects is more similar to Fig. 1 than Fig. 8 in that the bimetallic element 55' varies the compression of a spring 56' with change of temperature. Ordinarily the bimetallic element is so disposed that upon decrease in 90 ambient temperature, the compression of spring 56' is increased which increases the tension of spring 86 to offset the increased tension of spring 73 and vice versa. In this arrangement the bimetallic element should 95 be stiffer than spring 56' which in turn is stiffer than spring 86.

From the examples given, the manner in which temperature compensation may be applied to other types of spring governors is 100 105 readily understood and in its broader aspects my invention is not limited to the mechanisms specifically illustrated and described.

What I claim is:

1. A governor system for a motor comprising rotatable structure, a centrifugal member carried thereby, a spring opposing movement of said member by centrifugal force and rotatable with said structure, a stationary support, a member pivoted thereon and engaging said centrifugal member in the axis of rotation of said structure, a spring exerting a force on said pivoted member, the resultant of the forces exerted by said springs 110 determining the speed of said motor, and a thermostatic element controlling the force exerted by said second spring.

2. A governor system for a motor comprising rotatable structure, a centrifugal member carried thereby, a spring opposing movement of said member by centrifugal force and rotatable with said structure, a stationary support, a member pivoted thereon and engaging said member in the axis of rotation of 115 120 125

said structure, a spring exerting a force on said member, and a bimetallic strip whose stiffness is greater than the stiffness of said second spring varying the force exerted thereby with changes of temperature to compensate for the effect of the temperature changes upon said first spring.

3. A governor system for a motor comprising rotatable structure, a centrifugal member carried thereby, a spring system opposing movement of said member by centrifugal force comprising a spring rotatable with said structure, and a second spring, a stationary support, a member pivoted thereon and biased by said second spring into engagement with said member in the axis of rotation of said structure, and a bimetallic strip for varying the force exerted by said second spring with changes of temperature to maintain the stiffness of the governor spring system substantially constant throughout a range of temperatures.

4. A governor system for a motor comprising a centrifugal member, springs for producing forces whose resultant opposes movement of said member by centrifugal force, means for adjusting at least one of said springs to obtain a desired value of said resultant force, and a thermostatic element for varying the force exerted by at least one of said springs to maintain said resultant constant at the adjusted value irrespective of ambient temperature.

5. A governor system for a motor comprising rotatable structure, a centrifugal member carried thereby, a spring opposing movement of said member by centrifugal force and rotatable with said structure, means for adjusting said spring while said structure is stationary approximately to predetermine the speed of said motor, a stationary support, a member pivoted thereon and engaging said centrifugal member in the axis of rotation of said structure, a spring exerting a force on said pivoted member, means for adjusting said second spring precisely to determine the speed of said motor while running, and a thermostatic element controlling said second spring to maintain the motor speed constant at a fixed magnitude throughout a range of temperature.

ATHERTON H. MEARS.
